UNITED STATES PATENT OFFICE.

RAYMOND A. TEEL, OF BANGOR, PENNSYLVANIA.

BAG-LOCK.

1,141,022.

Specification of Letters Patent. Patented May 25, 1915.

Application filed April 12, 1913. Serial No. 760,693.

To all whom it may concern:

Be it known that I, RAYMOND A. TEEL, a citizen of the United States, residing at Bangor, in the county of Northampton and State of Pennsylvania, have invented new and useful Improvements in Bag-Locks, of which the following is a specification.

This invention relates to novel means for latching and automatically opening hand bags, suit cases and similar articles when the latching means is released.

The primary object of the invention is the provision of a novel form of catch or lock for the bag which is simple in construction, durable and cheap to manufacture and which releases simultaneously both ends of the bag when manually operated.

Another object of the invention is to provide a bag of this character having a central lock and end catches operated thereby in such manner that the end catches will latch or become operative to prevent the separation of the frame members first before the central catch is locked.

Further objects of the invention will appear as the following description is read in connection with the accompanying drawings, which form a part of this application, and in which:—

Figure 1 is a side elevation of an ordinary traveling bag with the improved type of catch thereon. Fig. 2 is a top plan view with the frame in open position. Fig. 3 is an enlarged view of the catch removed from the frame. Fig. 4 is a top plan view. Fig. 5 is an end elevation thereof. Fig. 6 is a longitudinal section through the catch looking in the direction of the arrow in Fig. 4. Fig. 7 is a similar view looking in the opposite direction. Fig. 8 is a top plan view with the slide removed.

In the specific embodiment of the invention as illustrated herein, 1 and 2 represent the separate parts of the frame, both of which are constructed of angle iron, as is usual, and the latter of which is somewhat smaller than the former so as to enter the same when the frame is closed. The section 1 has its legs provided with ears 3 and 4 separated a considerable distance, while the section 2 has somewhat similarly formed ears 5 and 6 adapted to engage the ears 3 and 4, as shown, and be held in operative position by a pivoting pin 7 which passes through the ears. Wound around this pivot and having their terminals crossed and con-

nected to the separate frame pieces 1 and 2 are springs 10 which normally act to open the frame when the catch is released.

The catch comprises a casing 14' having 60 depending ears 15 which are passed through the frame piece 1 and bent over against the same to prevent the removal of the casing. The latching bolt and slide are also connected by the key cylinder 21 and pivoted 65 to the upper portion of the bolt is a locking dog 22 having a depressed boss 23 adapted to snap into a depression or recess 24 formed in the top of the bolt. The casing, as shown, is provided with an offset ear 25 70 which when the dog is turned in the proper position will engage said ear and prevent movement of the slide to operate the latching bolt. When the key is placed in the key cylinder and turned it will engage the 75 notched end of the locking dog 22 and turn the same on its pivotal point, thus throwing the opposite end of the dog into engagement with the ear 25.

The bolt 19 is provided with a cut-away 80 portion 26 and operates partially over the slots 27 formed in the casing to receive the latching hooks 28. The extended finger 20 is passed through a slot 29 riveted to a longitudinally extending latching bar 30, the 85 ends of which are guided in clips 31 formed by punching out the metal of the frame piece 1, these openings being covered by brass plates 32 which take the place of the usual latching casings at the end of the bag. 90 The frame 2 is provided with apertured keeper members 34 and the rod 30 is provided with lateral extensions 35 adapted to engage said keeper members and lock the ends of the bag, the arrangement being such 95 that the lateral extensions 35 will engage the keeper members 34 prior to the complete entrance of the latching hooks 28 into the slots 27.

The frame piece 1 has bent up therefrom 100 a suitable lug or ear 36 and connecting this ear or lug with the finger 20 is a spring 37 which normally carries the locking bolt and slide back to normal position. It will be noticed that the connecting pieces 18 limit 105 the movement of the slide and locking bolt in any direction by engaging the end walls of the slot 16, and that the cut-away portion 26 in the bolt 19 permits the passage of one 110 of the locking hooks 28 and forms a member which engages the shoulder in said hook.

What I claim is:—

In a traveling bag, a pair of frame pieces, a casing secured to one of the frame pieces and having its top wall provided with an elongated slot and one of its side walls provided with spaced slots, one of the walls of the slot in the trap of the casing having a projection formed thereon, a locking member mounted within the casing and slidably engaging the said frame piece and having 10 a height approximately equal to the height of the interior of the casing, means on the opposite frame piece of the bag adapted to enter the slots in the side of the casing and engage the locking member to lock the frame 15 pieces when the bag is closed, an operating slide mounted on the top of the casing,

means extending from the elongated slot in the top of the casing and connecting the slide and the locking member to permit the member to be operated to disengage the 20 means on the second mentioned frame piece, for separation of the frame pieces, and means pivoted on the member operating to engage the projection on the wall of the slot in the top of the casing.

In testimony whereof I affix my signature in presence of two witnesses.

RAYMOND A. TEEL.
